The ornamental design for a footwear, as shown and described.

DESCRIPTION

FIG. 1 is a front, top and left-side perspective view of a footwear according to the new design,

FIG. 2 is a front side elevation view thereof;

FIG. 3 is a back side elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a back, bottom, and right side perspective view thereof.

The broken lines show portions of the design that form no part of the claim.
